SPINNING TYPE FISHING REEL

Howard R. Chapin, Franklin Park, Ill., assignor to Soreng Products Corporation, Schiller Park, Ill., a corporation of Delaware

Application May 20, 1955, Serial No. 36,129

Term of patent 14 years

(Cl. D31—4)

Fig.1.

Fig. 1 is a perspective view of a spinning type fishing reel, showing my new design;

Fig. 2 is a side view thereof; and

Fig. 3 is a front end view thereof.

I claim:

The ornamental design for a spinning type fishing reel, as shown.
